FLOUR SIFTER

Morris D. McCormick, Muncie, Ind., assignor to
McCormick Brothers Company, Albany, Ind., a
corporation of Indiana

Application October 27, 1949, Serial No. 5,735

Term of patent 14 years

(Cl. D44—29)

To all whom it may concern:

Be it known that I, Morris D. McCormick, a citizen of the United States, residing in the city of Muncie, county of Delaware, and State of Indiana, have invented a new, original, and ornamental Design for Flour Sifters, of which the following is a specification, reference being had to the accompanying drawings, forming part thereof, and in which

Figures 1 and 2 are side elevational views, taken at ninety degrees with respect to each other, of a flour sifter, showing my new design;

Figure 3 is a bottom view of the same.

I claim:

The ornamental design for a flour sifter, as shown.

MORRIS D. McCORMICK.
